UNITED STATES PATENT OFFICE.

JOHN EDWARD LEWIS OGDEN, OF LISCARD, ENGLAND.

LIQUID PUMP AND ELEVATOR.

Application filed May 28, 1923. Serial No. 642,082.

To all whom it may concern:

Be it known that I, JOHN EDWARD LEWIS OGDEN, a subject of the King of Great Britain and Ireland, and resident of Penshurst, Lincoln Drive, Liscard, in the county of Chester, England, have invented certain new and useful Improvements in and Relating to Liquid Pumps and Elevators, of which the following is a specification.

10 This invention relates to liquid pumps and elevators and has for its object to provide an improved construction and arrangement of pump in which leakage past the pump piston is reduced to a minimum without the employment of packing and like means which increase frictional losses in the pump, and in which the operation of the pump is automatically controlled in a simple and efficient manner.

20 My invention comprises a liquid pump or elevator in which the pump piston is exposed at one side to the liquid being pumped and at the other side to the operative pressure fluid, and is combined with a further piston acted upon by the pressure fluid to give the pump piston its suction stroke and if desired to assist in the delivery stroke.

25 My invention further comprises the improved automatic control valve for distributing the pressure fluid to the pump pistons and for exhausting such fluid.

30 My invention further comprises the improved details of construction and arrangement hereinafter described and claimed.

35 Referring to the two accompanying sheets of explanatory drawings:—

Figure 1 is a sectional elevation of a boiler feed pump constructed in one convenient form in accordance with my invention.

40 Figures 2 and 3 are respectively an elevation (partly in section) and a sectional elevation at right angles to Figure 2 illustrating a liquid elevator constructed in one convenient form in accordance with my invention.

45 The same reference letters in the three views indicate the same or similar parts.

Referring in the first place to Figure 1, the pump inlet valve is shown at *a* and the delivery valve at *b*. The pump piston is shown at *c* and the valve controlling the inlet and exhaust steam for operating the pump at *d*.

50 The piston *c* works in a cylindrical casing *e* to which is bolted a casing *f* in which

works the control valve *d* and which contains also a cylinder *g* having a piston *h* therein. The pistons *c* and *h* are interconnected by the rod *i*. The space above the piston *c* is in communication with the space above the piston *h* by the passage *j*.

Steam is supplied to the pump by the port *k* and exhausts therefrom at the port *m*. The valve *d* has a port *n* therein which when in coincidence with the port *k* allows steam to pass to the upper face of the piston *c* and by the passage *j* to the upper face of the piston *h*. The pressure of the steam on the said two pistons causes the downward and delivery stroke of the piston *c*.

With the pistons *c* and *h* in their raised positions as shown, that is at the end of a suction stroke and the commencement of a delivery stroke, the underside of the piston *h* is in communication with exhaust by way of the port *o*, groove *p*, the peripheral groove *q* around the valve *d* and the annular exhaust groove *r*. The underside of the head *s* of the valve *d* is also in communication with the underside of the piston *h* by way of the port *t*. The upper side of the head *s* of the valve *d* can be placed into communication with the upper side of the piston *h* by way of the port *u* when the piston *h* is forced downwards. The port *v* in the valve *d* serves to place the interior of the valve *d* and therefore the spaces above the pistons *c* and *h* in communication with the exhaust port *m*. The passage *w* serves to allow any water of condensation from the spaces around the upper end of the piston valve and of the piston *h* to pass to exhaust. The stud *x* prevents any turning movement of the valve *d*.

The upper side of the piston *c* is formed with a hollow or depression *y* in which water of condensation can collect and from which it is discharged by way of the passage *z* through the piston and the port *2* in the cylinder *e* each time the piston reaches the end of its suction or upstroke. The piston *c* is prevented from rotary movement by the key and keyway *3* between itself and the part *4* through which the rod *i* works.

The pump operates as follows:—Assuming the parts to be in the positions shown, steam has entered the spaces above the pis-

100

105

110

tons *c* and *h* and is also holding the valve *d* in its raised position. The pistons *c* and *h* are now propelled downwards and the delivery stroke takes place. The underside 5 of the piston *h* is in communication with exhaust. As the piston *h* approaches the end of such stroke, the port *u* is uncovered thereby and steam passes to the upper side of the head of the valve *d* and forces such 10 valve downwards. Such movement results in the closing of the steam port *k* and the placing of the interior of the valve *d* in communication with exhaust through the ports *v* and *m*. At the same time, the angular passage *q* around the valve *d* places the steam port *k* in communication with the underside of the piston *h*. The latter therefore rises and exhaustion of the spaces above the pistons *c* and *h* takes place. When the 15 piston *h* has risen sufficiently to uncover the port *x*, steam passes to the underside of the head of the valve *d* and raises such valve to the position shown in the drawings when the cycle of operations is repeated. 20

25 If the pump illustrated in Figure 1 be used for boiler feeding purposes, the pressure within the boiler is applied to the upper face of the piston *c* on the delivery stroke and the pressure of the liquid opposed to 30 said piston is equal to the said boiler pressure plus the pressure requisite to overcome the resistance of valves, bends and the like between the pump and boiler. There is therefore but little difference of pressures 35 at the opposite sides of the piston *c* so that practically no leakage from side to side of the piston occurs even though no packing rings are employed around the piston. The absence of packing rings reduces the friction 40 generated in the pump to a minimum.

The area of the piston *h* is proportioned to provide the necessary excess of pressure on the delivery stroke of the piston *c* to effect delivery against the desired head or 45 pressure.

The valve *d* is entirely automatic and is moved only when the piston *h* approaches the ends of its respective strokes.

50 Water of condensation which may tend to accumulate in the pump is effectually drained therefrom through the port 2 as hereinbefore explained.

55 Referring to Figures 2 and 3, the pump here illustrated is adapted for the raising of liquids and has means for automatically releasing from the surface of the liquid any air or vapour which may be compressed in the pump cylinder. The piston *c* has a port 9 therethrough which comes into line with the port 2 in the cylinder when the piston 60 is at the end of its delivery stroke so as to release any air or vapour from the surface of the liquid being delivered. When starting up, this arrangement makes the pump 65 self-priming. The valve *d* is of a type simi-

lar to the control valve of the form of pump shown in Figure 1. I provide small vent apertures 10, 11 in the valve casing to prevent air locks either above or beneath the valve head. In order to ensure that any dirt 70 which may enter the pump through the inlet valve *a* shall be discharged through the valve *b*, the bottom of the pump chamber 12 is made to slope downwards towards the valve *b*. The rush of the liquid being discharged 75 therefore carries all solid matter through the delivery valve and keeps the pump chamber clear. I provide automatic controlling means by which the pump is operated similar to the means described and claimed in 80 my prior U. S. Patent No. 1,478,792, dated December 25, 1923. Such means comprise as illustrated a piston type valve 13 which in its normal position allows a restricted 85 flow of pressure fluid to pass to the pump from the pipe 14. If, however, a vacuum is created by the pump in the pump suction pipe, this being an indication that the mouth of such pipe is sealed and that therefore 90 liquid is available for pumping, such vacuum acting on the diaphragm 15 at the side 16, causes the arm 17 to turn about its pivot 18 and raise the valve 13 so as to allow a 95 larger area for the passage of the pressure fluid to the pump.

In the valve arrangement shown in Figure 2, the underside of the piston *h* is not placed in communication with exhaust during the down or delivery stroke of the piston *c* but the pressure acting to raise the piston *h* is 100 balanced by the similar pressure acting on the upper side of the piston. The position of the valve as shown is that which it occupies during the delivery stroke. The 105 valve *d* in this example need not be prevented from rotary movement. If desired, the piston *c* may have a passage similar to *z*, Figure 1, for expelling water of condensation at the end of the suction stroke.

110 My improved pump is simple, compact and efficient. It is free from packing glands and piston packing and can be readily dismantled and re-assembled. It contains a minimum number of parts.

115 I claim:—

1. In liquid pumps and elevators, the combination with a pump piston, means for admitting liquid to be pumped to one side of the piston, means for admitting operative pressure fluid to the opposite side of the 120 piston, means for permitting the exhaust of the pressure fluid, a second piston connected with the pump piston having its opposite sides open to the exhaust means and the pressure fluid whereby to cause the suction stroke of the pump piston and to assist the delivery stroke of the latter.

125 2. In liquid pumps and elevators as claimed in claim 1, means for expelling any water of condensation from the pressure 130

fluid side of the pump piston at the end of the suction stroke of the latter, as set forth.

3. In liquid pumps and elevators as claimed in claim 1, a control valve for the pressure fluid provided with an enlarged head, the opposite sides of which are placed in communication with the opposite sides of

the further piston when the latter approaches the ends of its strokes in order to cause pressure fluid to move the valve in one or other direction, as set forth. 10

In testimony whereof I have signed my name to this specification.

JOHN EDWARD LEWIS OGDEN.
